UNITED STATES PATENT OFFICE.

WILLIAM ALLEN TEALL, OF EAU CLAIRE, WISCONSIN.

HOSE-NOZZLE.

No. 871,003.

Specification of Letters Patent.

Patented Nov. 12, 1907.

Application filed May 31, 1906. Serial No. 319,561.

To all whom it may concern:

Be it known that I, WILLIAM A. TEALL, a citizen of the United States, residing at Eau Claire, in the county of Eau Claire and State of Wisconsin, have invented a new and useful Hose-Nozzle, of which the following is a specification.

This invention relates to hose nozzles that are employed in connection with a length of hose for the purpose of sprinkling lawns and the street in front of the same.

To this end the main and primary object of the present invention is to provide a simple and efficient hose nozzle that shall act in the double capacity of a plain nozzle and sprinkler, and also be adapted for use in connection with an attachment whereby the water issuing from the nozzle may be broken up into a fine spray or mist.

With these and other objects in view which will readily appear as the nature of the invention is better understood, the same consists in the novel construction, combination and arrangement of parts hereinafter more fully described, illustrated and claimed.

In the accompanying drawings:—Figure 1 is a perspective view of a hose nozzle constructed in accordance with this invention. Fig. 2 is a central longitudinal sectional view thereof with the removable spray cap attached thereto. Fig. 3 is a detail in perspective of the removable spray cap.

Referring to the accompanying drawings, 1 designates a nozzle tube constructed of suitable metal and in the usual manner and provided at one end with the interiorly threaded attaching collar 2, which provides means for readily attaching and detaching the nozzle to and from an ordinary hose in the usual manner, and at its opposite end the said nozzle tube is branched to form two or more separate inwardly curved branch jet arms 3. The branch jet arms 3, are formed integral with the nozzle 2, and are curved or bowed inwardly toward each other to convergently dispose the outer discharging ends thereof, whereby the streams of water that issue from the said jet arms will meet or cross at a point slightly beyond the same, and under the force of the head of water will break up into a fine sprinkle that will be thrown quite a distance beyond the nozzle in order that lawns or other places may be quickly and readily sprinkled. At their outer discharging ends both of said jet arms 3, are provided with the annular rounded knobs 4, and one of said jet arms is further provided at a point intermediate of its ends with a tapered valve bearing 5, to accommodate therein the turning plug 6, of an ordinary thumb valve 7, whereby means shall be provided for cutting off the flow of water from that particular jet arm when it is desired to throw a solid stream

from the other valveless jet arm. By reason of the curvature of the said jet arm it will be readily understood that when the hose, together with the nozzle, are laid flat on the ground and the flow of water cut off from the valved jet arm, and the other jet arm having its tip end disposed upward, a solid unbroken stream will be thrown upward at an angle of about forty-five degrees, thereby dispensing with the necessity of having a support for holding up the nozzle when a single stream is left running.

When it is desired to break up the sprinkle caused by the meeting of the two streams from the jet arms, into a fine spray or mist, the removable flared spray cap 8, is employed. The spray cap 8, is of a substantially conical shape flaring outwardly, and is provided at one end with the flared attaching neck 9, having therein a screw groove 10, that is adapted to engage over the annular rounded knobs 4, at the outer extremities of the jet arms 3, said flared attaching neck 9, projecting a distance beyond the connection of the groove thereof with said rounded knobs, in order to snugly embrace a portion of the outer curved ends of the jet arms 3, and firmly secure the cap in position on said arms. The outwardly flared or conical spray cap 8, is provided at its outer circular edge with the turned retaining flange or bead 10°, that is adapted to engage over the edges of the wire gauze disk 11, which provides means for breaking up the sprinkle caused by the meeting jets of both jet arms into a fine spray or mist that is spread over a large area, and when only one of the jet arms is allowed to run with the spray cap attached in position, the stream of water from that jet arm will be broken up into a sprinkle that will be discharged to a greater distance than when the two streams are running with the spray cap on the nozzle. At this point it is to be noted that the effectiveness of the spray cap is due to the use of the wire gauze disk which produces an entirely different result from the ordinary rose jets that consist of a perforated plate or disk of sheet metal. These perforated plates or disks of sheet metal simply retard the flow of water causing it to break up into thin streams or to fall in drops, whereas by the employment of a wire screen or gauze, there will be no material resistance to the flow of water from the nozzle, even though the stream of water is discharged under considerable pressure, and as the water under force passes through the wire screen or gauze it is broken up into a fine spray without causing any drip that is usual in the ordinary rose jet, and therefore the herein-described spray cap can be readily attached and detached without wetting up the hands and feet of the operator.

Changes in the form, proportion and the minor

details of construction may be resorted to without departing from the principle or sacrificing any of the advantages of this invention.

Having thus described the invention, what is claimed and desired to be secured by Letters Patent is:—

- 5 1. A nozzle, comprising a tube having spaced jet arms projecting therefrom, and a spray cap detachably engaged with and supported by both arms and furthermore having a common chamber that receives the discharge from both arms, said chamber having a foraminous discharge wall.
- 10 2. In a hose nozzle, the combination with convergently disposed branch jet arms having the discharged ends spaced apart and provided with enlargements, of a spray cap supported by and detachably mounted on the arms, said cap having a neck that surrounds and is engaged with the
- 15

discharge ends of both arms, said neck having an interior seat that receives the outer sides of the enlargements and said cap having a foraminous wall.

3. A nozzle comprising a tube having spaced integral branch arms, a turning plug located in one of the arms for cutting off the flow of liquid therethrough, a flared spray cap having a neck that is detachably engaged on and supported by the outer ends of the branch arms, and a screen extending across the outer flared end of the cap.

In testimony, that I claim the foregoing as my own, I have hereto affixed my signature in the presence of two witnesses.

WILLIAM ALLEN TEALL.
